PROGRAM PRESELECTING AND CONTROL APPARATUS

Oscar Goldman, Portland, Oreg.

Application August 2, 1952, Serial No. 302,350

1 Claim. (Cl. 161—1)

This invention relates to improvements in electrically timed apparatus for preselecting and controlling the tuning in of radio receiving sets.

The principal objects of the invention are to provide apparatus of this character which is of simple, efficient, durable construction, readily adaptable to various types of radio receiving sets and which can be set in advance to automatically tune in one or more selected, predetermined stations at selected, predetermined times for predetermined successive or intermediate periods of time, and also set to establish silent intervals. The invention is readily adaptable, with a minimum amount of wiring and compact arrangement of time-selector and manually actuated station-selector switches, to a standard 12-hour clock, in which there are 48 fifteen-minute intervals in every 12 hours of operation of the clock.

These and other objects will appear as my invention is more fully hereinafter described in the following specifications, illustrated in the accompanying drawings, and fully pointed out in the appended claim.

Figure 1 is a front elevation of an electric time clock and time and station-selector switches made in accordance with my invention and with a fragment broken away.

Figure 2 is an enlarged sectional side elevation taken approximately along the line 2—2 applied to the clock in Figure 1.

Figure 3 is a sectional front view taken approximately along the line 3—3 of Figure 2 and illustrating in addition thereto the wiring diagram between the time-selector switches, the station-selector switches, and the radio receiving set.

Figure 4 is a detail view of a modified form of time-selector switch.

Figure 5 is a sectional end view taken along the line 5—5 of Figure 4.

Figure 6 is a sectional view taken along line 6—6 of Figure 4.

Figure 7 is a fragmentary view of a modified form of spring contact.

Figure 8 is a side view of Figure 7.

Referring now more particularly to the drawings:

With particular reference to Figures 1 and 2, reference numeral 1 indicates generally an electric time clock disposed within a housing having a front wall 2, and rear wall 3 to which is secured a Telechron motor 4, connected in its own separate electrical circuit for actuating the clock in the conventional manner.

The clock is mounted upon the top wall of a cabinet 5 upon whose front wall 6, which serves as a control board, is rotatably mounted a plurality of station-selector knobs 7, each provided with a pointer 8 for selecting a radio station whose call letters are inscribed on the front wall of the cabinet 5 concentrically with the radius of movement of the pointer 8. There are 48 station-selector knobs 7, representing and corresponding with the 48 fifteen-minute intervals in a 12-hour period of time, and as indicated by the graduations 9, appearing on the face 10 of the clock 1. The knobs 7 are arranged in six hori-

2

zontal rows of eight each, and as all of the rows, except for their time markings, are identical, a description of one row will suffice for all.

In Figure 3, I have illustrated the horizontal row covering the period of time between 6 o'clock and 8 o'clock which can be either a. m. or p. m. and divided into fifteen-minute intervals as shown so that any or all of the stations indicated generally at 11 may be selected for tuning in at any desired time between 6 o'clock and 8 o'clock by merely rotating the knobs 7 to the station or stations selected. The pointers 8 correspond with the movable switch arms 13, shown in Figure 3, and each switch arm is adapted to make electrical contact with individual fixed contacts 14, 15, 16, and 17. All of the contacts in each horizontal row are interconnected by wires 18, 19, 20, and 21, respectively.

Surrounding the face of the clock and extending through the front wall 2 thereof is a plurality of time-selector switches generally indicated at 22 spaced apart at fifteen-minute intervals corresponding with the graduations 9 on the front of the face of the clock. As best illustrated in Figures 2 and 3, each switch comprises a plunger 23 of square formation in cross section and slidably mounted at its front end in a square aperture 24 in the front wall 2 of the clock housing, and at its opposite end in a square bearing 25 secured to and extending through the back wall 3 of the clock housing. The front end of the plunger 23 is provided with any approved type of finger grip 26 for convenience in manipulating the plunger from the full to the dotted-line position, shown in Figure 2. Mounted upon the plunger are two bearing brackets 27 and 28, rotatably supporting a roller 29 tapered at one of its ends as at 30. The bracket 27 serves as a limit stop for the inward movement of the plunger 23 when the bracket strikes the inner end of the bearing 25. The bracket 28 serves as a limit stop for the plunger in the opposite direction when the bracket strikes the front wall 2 of the clock housing. Each bearing 25 is connected by a wire 31 with its respective switch arm 13, as shown in Figure 3.

The motor 4 of the clock drives a hollow tubular shaft 32, to whose outer end is secured the hour hand 33 of the clock. Rotatably mounted inside the shaft 32 is another shaft 34, to whose outer end the minute hand 35 of the clock is secured. The front end of the shaft 32 is rotatably mounted in a bearing 36 formed in the front wall 2 of the clock housing and is surrounded by a disc of electrical insulation 37 to which is secured by any suitable means a metal disc 38. Both discs are formed with aligned, enlarged central openings 39 of greater inside diameter than the outside diameter of the shaft 32 to prevent any danger of a short circuit. The opposite or inner end of the shaft 32 (not shown), in like manner, extends through companion discs 37A and 38A and into operative engagement with the clock motor 4. Secured to the shaft 32 by means of nuts 40 is one end of an arm 41 of electrical insulating material, having a pair of yieldable electrical contacts 42 and 43 insulated from each other and electrically connected by wires 44 and 45, respectively, to spring brackets 46 and 47, respectively, secured as at 48 to both sides of the arm 41. Brackets 46 and 47 are provided with rollers 49 and 50, respectively, which are held in permanent rolling contact with the discs 38 and 38A, respectively. The disc 38 is connected by wire 51 to one side of a source of electrical energy. The disc 38A is connected by wire 52 to one side of a switch 53 carried by the radio receiving set 54, and whose opposite side is connected by wire 55 to the other side of said source of electrical energy.

The wires 18, 19, 20, and 21 in Figure 3, which interconnect their respective spaced apart, fixed contacts 14, 15, 16, and 17, respectively, as aforesaid, are connected

by wires 56, 57, 58, and 59, respectively, to conventional radio-selector switch-actuating relays 60, 61, 62, and 63, respectively, whose opposite sides are connected by wires 64 and 65 to the side of the source of electrical energy indicated by the wire 55. Thus, it will be seen that when the yieldable spring contacts 42 and 43 are in contact with any one of the rollers 29 of the plunger switches, a circuit will be closed from the side 51 of the source of electrical energy through disc 38, roller 49, spring bracket 46, wire 44, spring contact 42, roller 29, spring contact 43, wire 45, spring bracket 47, roller 59, metal disc 38A, wire 52, through radio switch 53, then back to the other side of said source by wire 55. At the same time, the other electrical circuit will be closed from one side 51 of the source through disc 38, roller 49, bracket 46, wire 44, spring contact 42, roller 29 with which the contact 42 happens to be in contact, through the plunger shaft 23, bearing 25, wire 31, switch 13, any one of the fixed contacts 14, 15, 16, and 17 in contact with said switch arm, then through the corresponding one of said wires 18, 19, 20, and 21 and the respective one of said wires 56, 57, 58, and 59, into one side of said respective relays, then back to the other side 55 of the power line through wires 64 and 65.

Operation of the invention is as follows: For example, the time of day or night shown by the clock in Figure 1 is between 7 o'clock and 15 minutes after 7, or in other words, approximately in the middle of a program which started at 7 o'clock and will finish at 7:15 over station "KGW," represented by the row of interconnected contacts 14 having the switch arm 13A in contact with the contact 14A marked 7 o'clock. The circuit is closed from one side 51 of the source of electrical energy to the other side 55 thereof through the electrical connections above described. The relays 66, 61, 62, and 63 are of the conventional type, which when energized will automatically tune in the particular stations to whose settings they are connected within the radio receiving set. Accordingly, station "KGW" will remain tuned in as long as the switch arm 13A remains in contact with the contact 14A marked 7 o'clock, or as long thereafter as the other switch arms are in contact with the advanced contacts of fifteen-minute intervals. In other words, if it is desired to maintain station "KGW" tuned in continuously from 6 o'clock to 8 o'clock, it is merely necessary to move all of the contact arms 13 into contact with all of the fixed contacts 14. The same applies to the other stations "KOIN," "KEX," and "KPOJ," represented respectively by the rows of fixed contacts 15, 16, and 17. When it is desired to tune in a station at some future time, it is merely necessary to rotate the switch arm 13 into contact with that station at the desired time, then push the corresponding plunger switch inwardly so that its respective roller 29 will be disposed in the path of movement of spring contacts 42 and 43 as the spring contacts are moved in a clockwise direction with the hour hand of the clock. When a program is completed at the end of any selected period of time, the circuit to that station will be broken as the spring contacts 42 and 43 move away from the roller 29 with the arm 41 as it moves around with the hour hand of the clock.

The modified form of time-selector switch shown in Figures 4, 5, and 6 comprises a crank shaft 66, rotatably mounted in bearings 67 and 68, secured to the front and rear walls, respectively, of the clock housing. The crank portion of the shaft is provided with a roller 69 for elec-

trical contact with either form of the spring contacts carried by either arm 41 or 41A, secured to the hour hand of the clock, as aforesaid, when the roller is in the elevated, full-line position, shown in Figure 4. The forward end 5 of the crank shaft extends through the front wall of the clock housing and is provided with a turning knob 70 for swinging the roller 69 to either the "On" or to the "Off" 10 positions, shown in Figure 5. For maintaining the roller in the "On" position, I provide a latch in the form of a 15 spring arm 71, secured as at 72 to the interior of the front wall 2 of the clock housing. Pins 73 and 73A extend inwardly from the interior of the front wall 2 of the clock housing and are located in the path of movement of the crank portion of the shaft 66 to serve as limit stops for the shaft and roller 69 when swung to either the "Off" or "On" positions.

The modified form of spring contact, shown in Figures 7 and 8, consists of a strip of spring metal secured at 20 one of its ends as at 74 to the outer end of the arm 41A and connected to the wire 44A, which is the equivalent of the wire 44 in Figure 2. The contact is looped as shown so that its opposite and free end forms a movable contact 75, adapted to make and break contact with a fixed contact 76, secured to the outer end of the arm 25 41A and connected to the wire 45A, which is the equivalent of the wire 45 in Figure 2. The circuit between the contacts 75 and 76 is closed as long as the looped portion of the contact is in contact with either of the 30 rollers 29 or 69 of either form of time-selector switching mechanism. The central portion of the looped portion of this spring contact is projected forwardly or outwardly as at 77. The length of the projection is equal to the distance it will travel in 15 minutes over any one of the rollers of the switch mechanism with which it 35 is in contact.

While I have shown particular forms of embodiment of my invention, I am aware that many minor changes 40 therein will readily suggest themselves to others skilled in the art without departing from the spirit and scope 45 of the invention. Having thus described my invention, what I claim as new and desire to protect by Letters Patent is:

A time controlled periodic switch comprising in combination a motor-driven time clock and a housing therefor, the clock having an hour hand and a minute hand driven by two independent shafts extending through and insulated from two spaced apart contact discs, a rotary arm of insulating material secured at one of its ends to the shaft of the hour hand for rotation therewith, a pair 50 of contacts secured to the opposite end of said rotary arm, a plurality of spaced apart time-selector switches arranged circumferentially about the face of the clock housing, each selector switch comprising a shaft mounted in the front and rear wall of said housing, means carried 55 by the shaft of each selector switch for movement into and out of contact with said contacts for closing a circuit there-across, and means mounted on said rotary arm in constant contact with said spaced apart contact discs and electrically connected to said contacts.
